UNITED STATES PATENT OFFICE.

ARTHUR W. HERBERT, OF YOUNGSTOWN, OHIO, ASSIGNEE TO THE GENERAL FIRE-PROOFING COMPANY, OF YOUNGSTOWN, OHIO, A CORPORATION OF OHIO.

ADJUSTABLE CEILING-HANGER.

1,096,896.

Specification of Letters Patent. Patented May 12, 1914.

Application filed February 25, 1913. Serial No. 750,877.

To all whom it may concern:

Be it known that I, ARTHUR W. HERBERT, a citizen of the United States, residing at Youngstown, in the county of Mahoning and State of Ohio, have invented certain new and useful Improvements in Adjustable Ceiling-Hangers, of which the following is a specification.

This invention relates to an improvement in that class of building structures known as "hanging ceilings," wherein the ceiling structure is suspended from a support located above the same.

More specifically the invention has in view a novel hanger for a ceiling of this character, including a definite provision for an accurate and proper adjustment of the supporting means.

The present method of supporting hanging ceilings is to secure the supporting rods at the top to a beam and then bring them down and bend around the joists, adjusting the length of the supporting element by taking up or letting out at the bend around the joist. This crude adjustment is unsatisfactory, involves a considerable degree of labor, and loss of time. Accordingly, the present invention has in view the elimination of the disadvantages attendant to the old method and provides a simple, durable, and inexpensive device that will effectively perform the desired functions.

With the above and other objects in view, the invention consists in the novel construction, combination and arrangement of parts, hereinafter more fully described, illustrated and claimed.

The invention is necessarily susceptible of structural modification, but a preferred and practical embodiment thereof is shown in the accompanying drawings, in which—

Figure 1 is a general elevational diagram showing the application of the invention. Fig. 2 is an enlarged detail view of the adjusting means. Fig. 3 is a side elevation of the parts shown in Fig. 2. Fig. 4 is a detail view showing the form of spanner key 15 preferably used for making the desired adjustment.

Similar reference characters designate corresponding parts throughout the several figures of the drawings.

Referring specifically to the details of construction shown in the accompanying drawing, the reference character R design-

nates a two-part supporting rod, comprising upper and lower sections designated by the references 2 and 3 respectively. The upper section 2 is adapted to be bent around or equivalently attached to a beam B as shown at 4 so as to hold the same in firm engagement therewith, and the lower rod section 3 is designed to be suitably engaged with, as by a hook 5, the ceiling element 6. The adjacent ends 7 and 8 of the two rod sections 2 and 3 are respectively inserted and rotatably held in suitable bearing openings 9 and 10 of an adjusting disk 11. Normally these rod sections are in alignment as shown in Fig. 2.

The adjusting disk 11, which is made preferably of strong flat metal is also provided with the diametrically disposed key receiving openings 12, which are equidistant from the axis of the disk, and whose axes are in the circumference of a circle which is larger than the circumference of the circle in which lie the axes of the openings 9 and 10. The said disk 11 is further provided with a plurality of marginal radial slits 13 which extend inwardly from the periphery thereof a short distance, thereby forming a plurality of bendable locking tongues 14 which normally are undisplaced and lie within the plane of the disk body.

With the adjusting disk and sections of the supporting rod in a position as shown in Fig. 2, and said rod sections respectively engaged with the upper supporting beam and with the ceiling element 6, the opposite studs 16, of the spanner key 15 are inserted in the tool receiving openings 12 on the adjusting disk 11. Then by grasping the handle 17 of the spanner key 15, the adjusting disk 11 is rotated and acts as a lever to cause the lower rod section to be raised to the desired position. When this has been done any one of the locking tongues 14 which is directly beside the section 2 of the supporting rod is bent outwardly from the plane of the disk so that the edge thereof abuts against the rod section 2 thereby preventing the disk from being pulled back to its initial position by the weight of the ceiling. A further locking effect is secured by bending another one of the tongues 14 into locking engagement with the rod 3 thereby insuring additional safety in maintaining the supporting rod in its locked adjustment.

From the foregoing description it will be

evident that various changes in the proportion and details of construction may be resorted to without departing from the spirit or sacrificing any advantages of the invention.

5 I claim:

1. An adjustable ceiling hanger comprising a sectional supporting rod, and a manually operated lever device supported by and 10 adjustably connecting the rod sections.
2. An adjustable ceiling hanger comprising a sectional supporting rod, and a rotatable adjusting device journaled on and connecting the two rod sections and provided 15 with locking means.
3. An adjustable ceiling hanger comprising a pair of supporting rods, and a rotatable adjusting disk journaled on both rod sections, said disk being provided with locking means for securing it in any adjusted 20 position.
4. An adjustable ceiling hanger comprising a pair of supporting rods, a rotatable

adjusting disk journaled on both rod sections, said disk being provided with a marginal series of normally undisplaced bendable locking tongues for securing it in any 25 adjusted position.

5. An adjustable ceiling hanger including a sectional supporting rod, an adjusting disk provided with aligned openings 30 adapted to receive the adjacent ends of the said sectional supporting rod, said disk also provided with diametrically disposed tool receiving openings, and bendable marginal 35 tongues formed around the periphery of the adjusting disk adapted to be bent up from the plane of the disk body to lock the sections of the supporting rod in their adjusted position.

In testimony whereof I hereunto affix my signature in the presence of two witnesses.

ARTHUR W. HERBERT.
